(No Model.)

V. H. ERNST.

MACHINE FOR EASING THE LEVERS OF TYPE WRITERS.

No. 335,118.

Patented Feb. 2, 1886.

WITNESSES,

INVENTOR

E Van Duff
Moeai Hittitevader

Victor H. Ernst

UNITED STATES PATENT OFFICE.

VICTOR H. ERNST, OF JERSEY CITY, NEW JERSEY.

MACHINE FOR EASING THE LEVERS OF TYPE-WRITERS.

SPECIFICATION forming part of Letters Patent No. 335,118, dated February 2, 1886.

Application filed October 14, 1885. Serial No. 179,879. (No model.)

To all whom it may concern:

Be it known that I, VICTOR H. ERNST, of Jersey City, in the county of Hudson and State of New Jersey, have invented a new and improved machine for easing the levers of typewriters preparatory to their being placed in the type-writer, of which the following is a full, clear, and exact description.

In the operation of writing-machines where-
10 in the types strike a common central point on the ribbon it is of the utmost importance that the type-carrying levers have an easy and free movement in their hangers, for should they be allowed to become loosened they will jog-
15 gle from one side of their hangers to the other, and as a result the printing of the type will be uneven. Ordinarily when the type-levers are set in the writing-machines they have to be worked till the friction at the pivoting-point
20 eases the levers on their hangers sufficiently to allow the desired freedom of movement on their pivots, which takes considerable time. If this is not done, the natural friction at this point when the writing-machine is being op-
25 erated, which is very great in new machines, will necessitate a continual easement of the type levers on their pivots. To avoid the ne-
cessity of this easement of the levers after having been fitted in the writing-machine, I have
30 contrived the present invention, which is known as a "jiggling-machine." It consists, essentially, of a series of clamping-heads or equivalent devices so arranged on a common base that a rapid reciprocating motion may
35 be imparted to them. Into these clamping-
heads the hangers carrying the type-levers are placed, and by the rocking motion a friction is produced between the type-levers and the jaws of their hangers, wearing them uni-
40 formly, and thus effecting the desired ease-
ment, which they retain permanently. As herein explained, this has prior to this invention been done by the continued operation of the writing-machine.

45 Reference is to be had to the accompanying drawings, forming part of this application, in which similar letters of reference indicate corresponding parts in all the figures.

Figure 1 is an end elevation of my invention with the type-levers in position in the clamping devices. Fig. 2 is a front elevation of the machine. Fig. 3 is a plan view of a

section of the machine. Fig. 4 is an end view of the shaft to which is eccentrically attached the connecting-rods that impart a vertical move- 55 ment to the upper cross-bar carrying the clamp-
ing devices. Fig. 5 is a section of the same on the line *xx*.

A A indicate the standards of the machine, which are provided with bases B B. 60

C is a cross-bar, which is connected to the sliding blocks or plates D, that are fitted in dovetail or other grooves in the projecting heads A' of the standards A A.

The sliding blocks or plates D are connected 65 by means of the connecting-rods E to the shaft F, which has its bearings in the rearwardly-projecting lugs A' of the standards A A.

Upon one or both ends of the shaft F is se- 70 curely fitted a headed sleeve, H, in a groove in the head of which is fitted an adjustable block, I, to which the connecting-rods E are eccentrically attached—as, for instance, at *i*, Figs. 4 and 5.

It will be readily seen that the play of the 75 connecting-rods E, and consequently the move-
ment of the sliding blocks D and bar C, is con-
trolled by means of the block I, which can be
moved to bring the point of attachment of the
connecting-rods E nearer to or farther from 80 the center of the headed sleeve H. The block
I is securely held in a given position by the
binding-screws *i*', or equivalent means.

Motion is imparted to the shaft F by a belt 85 from any convenient motive power by means of pulleys G, of the ordinary or any approved construction.

Although I have shown in the drawings the actuating devices arranged in duplicate—that is, on both ends of the machine—it will be 90 understood that the latter can be used to ad-
vantage with these devices arranged on one side only.

The cross-bar C is provided with a series of clamping-heads, C', each of which is capable 95 of carrying two type-levers, L. The clamp-
ing-plate *c* of each of these clamp-heads is provided with a spring, *c'*, which serves to keep the clamp-plate raised for the ready in-
sertion of the type-lever hangers J, and with 100 a binding-screw, *c*², for firmly holding the said type-lever hangers in the clamp-heads.

*c*³ are clearance-grooves for the jointed ends of the type-levers.

A stationary cross-bar, K, is provided below and partly or entirely out of the vertical plane of the cross-bar C, and provided with clamping-heads k, similar in construction and 5 in number to those on the latter, and in these clamping-heads k the several connecting or operating rods L' of the several type-levers L are rigidly held. Although only four of these clamping-heads are shown on each cross-bar, 10 in practice the machines are constructed with forty, (more or less,) thus allowing eighty (more or less) type-levers to be operated upon at one and the same time.

To support the type-levers in line while being inserted in and removed from the clamping-heads, I have provided the bar M, the swinging arms N of which are pivotally connected to the arms O, the latter being attached to the standards A A of the machine. By 15 reason of the arms N being slotted at their outer ends the bar M can be brought nearer to or farther from the ends of the said arms N, should it be found desirable at any time. When all the type-levers are in place in the 20 clamping-heads, the bar M is swung down, as shown in dotted lines in Fig. 1, and in full lines in Fig. 2, and may be again raised when the type-levers are to be replaced by another lot. When the shaft F is rotated, the connecting-rods E thereon cause the blocks D to slide 25 up and down in their bearings, and being connected to the cross-bar C the latter is given a rapid vertical reciprocating movement. The operating-rods L' of the type-levers L being 30 held rigidly in the clamping-heads k of the cross-bar K, the movement of the cross-bar C causes a rapid swinging of the type-levers on their pivots. After being thus operated upon by the machine the desired freedom of movement is given them, and thus the desired ease- 35 ment that has heretofore taken considerable time is obtained very readily, and a saving of time effected.

The special mechanism herein described is 40 the preferred mode of carrying out my invention; but I do not wish to be understood as limiting myself to the particular means shown and described, for it is evident that a variety of means may be provided for actuating the bar 45 carrying the type-levers, and for holding the latter while being operated upon.

Having thus fully described my invention, I claim as new and desire to secure by Letters Patent--

1. The improved mode of easing type-levers 55 in their hangers, consisting in subjecting the said levers to a rapid reciprocating motion in their hangers until the desired easement is obtained preparatory to their being inserted in the writing-machine, substantially in the manner and for the purpose set forth. 60

2. In a machine of the character described, the combination of a reciprocating cross-bar, a rigid cross-bar below the same, each bar being provided with a like number of clamps, 65 for the purpose set forth, and means, substantially as described, for actuating the reciprocating bar, as and for the purpose specified.

3. In a machine of the character described, the combination, with the standard A, of a 70 cross-bar, C, having arranged thereon a series of holding or clamping devices, C', for holding the type-levers L, a rigid cross-bar, K, having clamping devices k, for rigidly holding the operating or connecting rods L' of the type-levers, and means for imparting a rapid reciprocating motion to the bar C, substantially as 75 and for the purpose specified.

4. The combination, with the standards, of a reciprocating cross bar, a sliding block or 80 plate connected thereto, and a connecting-rod connected to the sliding block and to the operating-shaft, substantially as described.

5. The combination, with the reciprocating bar, of clamping-heads mounted thereon, each 85 provided with means for holding the clamp-plates raised for the ready insertion of the type-lever hangers, substantially as described.

6. The combination, with the standards, formed near their tops with grooved heads or 90 shoulders, of the clamp-carrying cross-bar C, the sliding blocks D, the connecting-rods E, shaft and pulleys F G, and the cross-bar K, substantially as described.

7. The combination, with the operating- 95 shaft, of headed sleeve H, carrying adjustable block I, substantially as described.

8. In a machine of the character described, the combination, with the standards A and reciprocating bar C, carrying clamps or 100 holders, of the swinging frame consisting of arms N and bar M, substantially as and for the purpose specified.

VICTOR H. ERNST.
